UNITED STATES PATENT OFFICE.

WILLIAM SANDERS, OF ST. LOUIS, MISSOURI, ASSIGNOR TO THE ONE MINUTE CHURN COMPANY, OF SAME PLACE.

DESIGN FOR A CHURN-DASHER.

SPECIFICATION forming part of Design No. 25,009, dated December 24, 1895.

Application filed September 23, 1895. Serial No. 563,441. Term of patent 7 years.

To all whom it may concern:

Be it known that I, WILLIAM SANDERS, of the city of St. Louis, State of Missouri, have invented a certain new and original design for Churn-Dashers, of which the following is a full, clear and exact description, reference being had to the accompanying drawings, forming a part hereof.

In the drawings, Figure 1 is a top plan view of a churn-dasher of my design. Fig. 2 is a vertical sectional view taken on the line 2 2 of Fig. 1.

The leading feature of my design consists in a body, which, when viewed in side elevation, is in the form of a double cone, one cone above the other, the upper one of which is much shorter than the lower one, but the sides of which are much more oblique.

1 indicates a body of conical form, the inclination of the sides of which is very slight, and surmounting said body 1 is a second coni-

cal body 2, the same being much shorter than the body 1 and the inclination of the sides of which is much greater than said first-mentioned body. The upper end of said second conical body 2 terminates in a tubular projection 3, the bore or aperture 4 of which passes downwardly through the conical body 1, and also the body 2. Formed in the under side of the conical body 1 is an approximately semi-circular recess 5, the walls of which are reversely curved near the margin of said recess.

I claim—

The design for a churn-dasher as herein shown and described.

In testimony whereof I affix my signature in presence of two witnesses.

WILLIAM SANDERS.

Witnesses:

JOHN C. HIGDON,
MAUD GRIFFIN.
